(57) **CLAIM**

The ornamental design for a tire, as shown and described.

DESCRIPTION

FIG. 1 is a side elevation view of the tire of my design; FIG. 2 is a side elevation view of the tire of my design, taken from the opposite side of that shown in FIG. 1; and, FIG. 3 is an enlarged, partial view of the tire taken along the line 3-3 of FIG. 1. The dash-dot-dot lines define the peripheral boundaries of the claim. The broken line disclosure in the drawings depicts environmental subject matter forming no part of the claimed design.
